Primary Examiner — Ian Simmons*Assistant Examiner* — Keith Frank(74) *Attorney, Agent, or Firm* — United IP Counselors, LLC(57) **CLAIM**

We claim the ornamental design for a vessel for a candle, as shown and described.

DESCRIPTION

This application is related to three other U.S. design patent applications, each of them filed on the same date herewith, and all of them also titled “Concrete Vessel for a Candle.” These three applications have been assigned U.S. application Ser. Nos. 29/587,097, 29/587,107, and 29/587,111, respectively, and all of them are incorporated by reference herein in their entirieties.

FIG. 1 is a perspective view of a vessel for a candle, showing our new design;

FIG. 2 is a side elevational view of the vessel, with all sides being identical;

FIG. 3 is a top plan view thereof; and,

FIG. 4 is a bottom plan view thereof.

The short-dashed broken lines in the central cavity of the vessel indicate environmental structure—the candle wax and wicks—that forms no part of the claimed design.
